HOT PLATE DISH COVER

James Edward Krilow, Atlantic City, N. J.

Original application July 18, 1950, Serial No. 11,246. Divided and this application November 5, 1952, Serial No. 22,150

Term of patent 14 years

(Cl. D44—15)

To all whom it may concern:

Be it known that I, James E. Krilow, a citizen of the United States, residing at Atlantic City, in the county of Atlantic and State of New Jersey, have invented a new, original, and ornamental Design for a Hot Plate Dish Cover, of which the following is a specification, reference being had to the accompanying drawing forming part thereof.

This application is a division of my co-pending application Serial No. D. 11,246, filed July 18, 1950, now Patent No. D. 168,462.

Fig. 1 is a top plan view of a hot plate dish cover showing my new design; and

Fig. 2 is a partial side elevational, partial vertical sectional view thereof.

I claim:

The ornamental design for a hot plate dish cover, as shown.

JAMES EDWARD KRILOW.
